UNITED STATES PATENT OFFICE.

CLEMENT HENRY STEVENS, OF LAS PALMAS, GRAND CANARY, CANARY ISLANDS,
ASSIGNOR OF ONE-HALF TO SUMMERS HUNTER, OF WALLSEND-ON-TYNE, ENGLAND.

PNEUMATICALLY-OPERATED PERCUSSIVE HAND-TOOL.

1,110,155.

Specification of Letters Patent.

Patented Sept. 8, 1914.

Application filed July 7, 1913. Serial No. 777,750.

To all whom it may concern:

Be it known that I, CLEMENT HENRY STEVENS, a subject of the King of Great Britain, residing at Las Palmas, Grand Canary, Canary Islands, engineer, have invented a new and useful Improvement in Pneumatically-Operated Percussive Hand-Tools, of which the following is a specification.

10 This invention relates to pneumatically operated percussive hand tools of the type in which a piston constituting a hammer is reciprocated by the admission of compressed air alternately to opposite sides of said piston, and to that class of apparatus in which the admission of compressed air to the opposite ends of the piston cylinder is controlled by means of a valve interposed between two sets of ports communicating with the opposite ends of the cylinder in which the piston or hammer works, each set of ports being alternately and automatically closed by said valve to admit air under pressure first to one end and then to the other end of said 25 cylinder to reciprocate the piston in the latter.

According to this invention the valve is in the form of a plate with flat faces, and these faces seat alternately on opposite sides 30 of a valve chamber having inlet and outlet ports extending from the valve seats on both sides of the valve. The inlet passages extend from opposite sides of the valve to a main air conduit, and the outlet passages extend from opposite sides of the valve to opposite ends of the cylinder in which the piston or hammer works. The pressure fluid acts upon the whole area of one face of the valve while passing from the inlet to the outlet 35 passages on the one side of the valve and closes the latter upon the inlet and outlet ports in the valve seat on the opposite side of the valve, the face of the valve on this side being now subjected to the pressure of the fluid over an area which is only that of the inlet.

A tool provided with the improved means for controlling the air supply is illustrated in the accompanying drawings, in which:— 50 Figure 1 is a longitudinal section of the tool, Fig. 2 a section on the line $x-x$ in Fig. 1, Fig. 3 is a view on the line $y-y$ in Fig. 1, showing a plan of the upper face of the lower block in which the valve chamber is

formed, Fig. 4 is a plan view of the upper 55 face of the upper block and Fig. 5 is a section on the line $z-z$ in Fig. 3, Fig. 6 is a view similar to Fig. 5 illustrating a modification in the arrangement of the ports.

The tool comprises, as is well known, a 60 handle 1 furnished with a main air valve 2 which controls the supply of air to a passage 4 formed at one end of a socket 5. The other end of this socket is screw-threaded to receive the rear end of the cylinder 6 in 65 which works a piston or hammer 7.

In carrying out the invention, I provide within the socket 5 and co-axially with the cylinder 6, two annular blocks 8, 9. The upper face of the lower block 9 is formed 70 with an elongated recess 10 to receive the valve 11 and in communication with the ends of the recess are ports or passages 12 and 12^c, which extend from the upper face of the block to the floor of the recess 10. The 75 ports 12 and 12^c, serve to admit air into the valve chamber 10 beneath the valve 11, which valve opens and closes an outlet port 13 formed midway of the chamber 10 in the block 9. 80

The upper block 8 is formed with inlet ports 12^a and 12^b which register with the ports 12, 12, in the lower block 9 and is also formed with an inlet port 13^a which is co-axial with the port 13 in the block 9. The 85 several ports 12, 12^a, 12^b, 12^c, 13 and 13^a are disposed to form a middle passage (13 and 13^a), an inner pair of passages (12^a and 12^b), and an outer pair of passages (12 and 12^c). On the forward or power stroke of the piston the air passes through the ports 13^a, 12^b, and 14, and on the return piston movement the air passes through the ports 12^a, 12, 12^c, and 13. The inlet port 13^a is opened and closed by the valve 11, which latter controls communication between the said port and outlet ports or passages 14, 14, extending upward from the lower face of the block 8 and radially to the inner periphery thereof. To retain the upper and lower blocks 100 8, 9, in the proper position relatively to the ports, the lower block 9 is provided with dowels 15 which engage in corresponding recesses 16 in the block 8.

The two blocks 8, 9, placed face to face 105 are held within the socket 5 by screwing the handle 1 upon the cylinder 6 at 17 so that the blocks are secured between the end of

the cylinder and the end of the socket. The ports 12^a, 12^b and 13^a in the upper block 8 communicate with the annular main air conduit 4 formed in the handle 1 or head 5 of the tool and controlled by the main valve 2. This valve is a hollow cylinder closed at one end by a head 2^a and works in a chamber 1^a which is formed in the head 1, and which chamber is formed with a seating 15 1^b to receive the head 2^a of the valve. Adjacent to the head 2^a of the valve 2 are openings 2^b formed in the cylindrical portion of the valve, and for operating the valve a spindle 18 is provided passing horizontally 15 through the head 1. One end of this spindle engages the head 2^a of the valve 2 while its opposite end is engaged by a trigger 19 pivoted at 19^a within the handle 1.

In the wall of the cylinder 6 is a passage 20 20 which establishes communication between the port 13 in the block 9 and that point of the cylinder where the stroke of the hammer 7 ends, while midway of the length of the cylinder are outlet passages 21 which communicate with the atmosphere.

The two blocks 8 and 9 are centrally bored to the diameter of the piston working chamber, and are mounted within the cylinder 6 coaxial with the axis of said chamber and 30 provide an extension of the cylinder, and within which the piston 7 works.

Fig. 6 illustrates a modification of the disposition of the ports in the blocks 8 and 9. In the block 8 are two adjacent ports *b*, *b'*, which serve for the inlet and one of these ports (*b*) communicates directly with one end of the valve chamber 10 on the one side of the valve 11, while the other port (*b'*) registers with a port *c'* which is formed in the block 9, and which port communicates by way of a passage *c* with that side of the valve 11 opposite to the port *b*. The outlets from the chamber 10 are provided by a port *d* formed in the block 9 and communicating between the valve chamber and the handle-end of the cylinder 6 in a manner similar to the port 14 shown in Fig. 5, while another outlet is provided by a port *e* formed in the block 8 and communicating 50 between the valve chamber 10 and a port *e'* formed in the block 9, which latter port communicates with the passage 20 in the cylinder 6.

The working of the valve 11 for reciprocating the piston 7 is as follows: When the handle 1 is grasped the fingers of the hand clasp the trigger 19 with the effect that the main valve 2 is pushed outward by means of the spindle 18, thus admitting compressed air into the passage 4, whence the air flows by way of the ports 11, 12 and 12^a to opposite sides of the valve 11. Assuming the piston 7 to be in the position shown in Fig. 1 and to have just reached the end of its stroke, 65 and the valve 11 to be seated so as to close

the port 13, the air flowing into the port 13^a passes by way of the port 14 into the cylinder 6 whence the air escapes owing to the outlet passages 21 in the cylinder being uncovered by the piston 7. This escaping air 70 reduces the pressure upon that face of the valve opposite to the ports 13^a and 14, and consequently the greater pressure of the air flowing through the ports 12^a, 12, lifts the valve 11 to close the ports 13^a and 14, with 75 the effect that communication is established between the ports 12 and 13. The compressed air now flows by way of the passage 20 into the cylinder 6 and acts upon the forward end of the piston 7 which is thus 80 driven rearwardly. Toward the end of the return stroke of the piston 7 the latter uncovers the outlet passages 21 with the result that the air pressure on that face of the valve opposite to the passage 20 is reduced 85 and the greater pressure acting upon the other face of the valve closes the valve upon the passage 20 and establishes communication between the ports 13^a and 14. The compressed air now flows by way of the port 14 90 into the rear end of the cylinder 6 and drives the piston 7 forward to strike the tool 22 at the end of the cylinder. This cycle of operations is repeated during the time the main valve 2 is open and a rapid 95 succession of blows is given by the piston 7 to the tool 22.

In order to prevent the piston 7 striking the head of the tool with force on its return or rearward stroke, the openings of the inlet 100 ports 12^a are throttled, as shown in Figs. 4 and 5, so that pressure of the air for the return stroke is reduced; the pressure required for returning the piston being less than that required for the working stroke.

To stop the reciprocation of the piston 7 the pressure of the fingers on the trigger 19 is released, whereupon the pressure of the air acting upon the head 2^a of the valve 2 closes the latter upon its seat.

Although I have described a particular construction of valve controlling means it will be obvious that the construction is susceptible of various modifications. For example, the valve chamber may be annular in 115 form to receive a correspondingly shaped valve, in which case the annular blocks are formed with several circularly arranged inlet ports which are disposed intermediately of the outlet ports, the latter being also circularly arranged.

What I claim as my invention and desire to secure by Letters Patent is:—

1. In a pneumatically-operated hand tool, the combination of a hollow cylinder having 125 an air chamber and a passageway leading therefrom; members located within said air chamber and centrally bored to axially register with the hollow cylinder and provide therewith a piston working chamber; a pis-

- ton operable in said chamber; said members provided with a recess, and having ports communicating with said piston working chamber and said passageway; and an air-controlled valve automatically operable in said recess to alternately open and close said ports whereby to operate the piston, and said piston working chamber having an exhaust opening, substantially as described.
- 10 2. In a pneumatically-operated hand tool, the combination of a hollow cylinder having an air chamber and a passageway leading therefrom to the head end of the cylinder; members located within said air chamber and having a plurality of registering apertures providing air ports, said ports communicating with said cylinder passageway and the piston working chamber at the other end of the cylinder, and a recess between 15 said members communicating with said ports; a piston; a valve operable within said recess; the ports for admitting air to said passageway having openings of relatively less cross section than the opening to the ports for admitting air to said other end of the cylinder whereby to produce variable pressure on said valve and effect the actuation of the same during the reciprocation of the piston; and said piston working chamber having an exhaust opening, substantially as described.
- 20 3. In a pneumatically-operated hand tool, the combination of a cylinder providing a piston working chamber and having an air chamber, and a passageway providing communication between the air chamber and the piston chamber; a controlling valve for said air chamber; a piston operable in the piston chamber; a pair of blocks located within said air chamber and having registering 25 pairs of ports and registering ports intermediate said pairs of ports, the adjacent faces of said blocks being cut away to provide a recess providing communication between the middle and inner pair of said 30 ports; a plate valve mounted to operate within said recess and automatically operable to open and close communication between said ports whereby to admit compressed air into said piston working chamber, and said piston chamber having an exhaust opening, substantially as described.
